GAME APPARATUS

John Grauer, Whitestone, N. Y.

Application November 7, 1933, Serial No. 696,931

5 Claims. (Cl. 273—89)

This invention relates to game apparatus and while it is herein illustrated in an apparatus whereby the game of baseball may be played, it is equally adapted to other games.

5 It is one object of the invention to provide a novel apparatus which may be operated by two persons, to play a game of baseball or the like in a realistic manner and in close similarity to the game as played on a regulation field with regulation equipment.

10 It is another object of the invention to construct an apparatus wherein the skill of the players with an element of chance, thereby greatly increasing the interest in the playing of the game.

15 In the accompanying drawings, I have illustrated one form of my invention, and in said drawings,

Figure 1 is a perspective view of a game apparatus constructed in accordance with the present invention,

Figure 2 is a top plan view thereof,

Figure 3 is a sectional view taken on the line 3—3 of Figure 2,

20 Figure 4 is a sectional view taken on the line 4—4 of Figure 2,

Figure 5 is a vertical sectional view taken on the line 5—5 of Figure 2,

25 Figure 6 is a fragmentary bottom plan view on an enlarged scale,

Figure 7 is a detail sectional view showing the manner in which one of the chute sections may be moved to control the flight of the missile, and;

30 Figure 8 is a detail perspective view of a portion of the mechanism.

Referring more specifically to the drawings, the game apparatus is, for the sake of convenience, mounted upon a suitable base 10. Mounted upon the base 10, in such a manner as to rotate relative to a fixed pointer 11, there is a play indicator 12, preferably in the form of a disk, the upper surface of which is divided into a plurality of segments bearing indicia designating various plays of the game to be played.

45 Mounted upon the base 10, there is a housing 15, the upper portion of which is formed with a chute 16, one end of which is wider than the other as the result of an angularly disposed side wall 17, and a straight side wall 18. The bottom wall of this chute 16, terminates as at 19, at a point short of the end wall 20, to provide a space between the end of the chute and said end wall 20, through which the missile designated 21, in 50 Figure 2, is free to pass. A portion of this open-

ing is closed by two trap doors 22, which operate in unison and, as illustrated in Figure 5, are pivotally mounted as at 23 to said end wall 20. These trap doors are spaced from each other and the space between said trap doors is adapted to permit of the passage of the missile 21, directly to an inclined chute 24, mounted beneath the space between the end 19 and the bottom of the chute and the end 20, thereof. The inclined chute 24, is beneath the space between the trap doors 22, and it delivers to a compartment 26, while the trap doors 22, deliver directly to a compartment 28.

55 So far as described the device operates as follows. The missile being rolled through the chute 16, will depending upon its direction of flight through the chute roll upon either of the trap doors 22, and be delivered to the central space thereby to the chute 24, and into the compartment 26, to designate a strike in the game of baseball. If, however, the trap doors 22, be lowered, the missile may enter the space uncovered thereby, in which case the missile will be delivered to the compartment 28, and indicate a ball in the game of baseball.

25 A chute 30, is employed to deliver the missile 21, to the chute 16. This chute 30, may be supported at its outer end upon a vertically movable standard 31, in such a manner that it may be rocked about its longitudinal axis, this being accomplished in the present illustration of the invention by the projecting member 32, which is positioned in an opening 33, in the standard 31. The inner end of the chute 30, is provided with an eye 34, which engages over a projecting member 35, and by this means the chute 30, may be rocked from right to left as indicated by dotted lines in Figure 7. Thus, one of the players who represents the side in the field may manipulate the chute 30, to direct the flight of the missile 21, therethrough, and also to direct its flight through the chute 16.

30 Means is provided to intercept and change the direction of flight of the missile 21, and this means comprises an impact member 40, movable across the chute 16. This impact member is carried by a vertical shaft 42, which shaft is operated by a coil spring 43, as in Figure 4, to cause the impact member to make a sweeping movement in a substantially horizontal plane 50 across the chute 16. This impact surface has a bat to engage the missile and is held out of position in the chute by the operator, preferably by his thumb, as shown in Figures 1 and 2.

35 In operation the missile is started through the 55

chute 30, its flight controlled by one player as heretofore described, the other player holding the impact member against operation by the spring 43, as illustrated in Figures 1 and 2. At 5 what he deems the proper moment the player in control of the impact member releases the same in an effort to intercept the missile 21, in its flight through the chute 16. If the impact member, when released by the player misses the 10 missile, the missile will pass to the end 19, of the chute and be delivered to the compartment 26, registering a strike against the player in control of the impact member. This result is always attained if the impact member misses the 15 missile in its flight through the chute 16, for the reason that the trap doors 22, are raised by releasing the impact member so that only the center space between the trap doors 22, is open and the missile must pass through this space to 20 the strike compartment. This closing of the trap doors is effected by a link 45, connected to an arm 46, which in turn is carried by the vertical standard 42, in such a manner that as the impact member swings across the chute 16, the 25 trap doors 22, will be moved to closed position. If, however, the player does not release the impact member, then the missile is free to enter either the compartment 26, or 28, depending upon its direction of flight and register either a strike or a ball, as the case may be.

Assuming, now, that the impact member in its movement across the chute 16, engages the missile and projects it to the right in Figure 5, the missile passes through the contracted portion 50, of the bottom of the chute 16, and falls upon a member 51, carried by a right angular lever 52, pivotally mounted as at 53, in a bracket 54, carried by the under face of the base 10, and causes this lever to rock about its pivotal point, and thereby 30 elevate its end 55. The end 55, of the lever 52, is weighted, as indicated at 56, in Figures 6 and 8, and this lever engages a shoulder 60, of a reciprocating bar-like member 61, which is mounted in guides 62, upon the under face of the base 10. This bar-like member 61, is moved in 35 one direction by a spring 65, one end of which is connected to a bracket 66, the other end being connected to an arm 67, projecting from the bar-like member. This bar-like member carries a 40 projection 68, which is adapted to engage the teeth 69, of a toothed wheel 70, carried on the lower end of the shaft 71, upon which the play indicator 12, is mounted. Thus as the bar-like member 61, is moved to the position shown in 45 full lines in Figure 6, the projection 68, will engage one of the teeth 69, of the toothed wheel 70, to effect a spinning action of said toothed wheel 70, and thus spin the play indicator 12.

From the foregoing it will be apparent then, 50 that each time the missile is dropped upon the member 51, the lever 52, will be rocked about its pivotal point 53, to release the bar-like member 61, to effect an operation of the play indicator.

Means is provided to set the tension of the 55 spring 65, of the bar-like member each time the impact member is moved to the position in which it is shown in full lines in Figure 1, and this means is herein illustrated as a curved arm 80, carried by the shaft 42, of the impact member, which arm 80, when the impact member is moved to the full line position shown in Figure 1, engages a projecting arm 81, upon the bar-like member 61, to move the same to the dotted line position in which it is shown in Figure 6 in which 70 position it is held by engagement of the lever 52

behind said shoulder 60. If, now, the impact member 40, be released, it will move in the direction opposite to that indicated by the arrow in Figure 6, and will not effect any movement of the bar-like member 61, the bar-like member 61, being released to the action of its spring 65, only by a rocking of the lever 52, as heretofore described. The bar-like member 61, has an offset end 85, which when in its set position, engages between two of the teeth 69, of the toothed wheel 70, to prevent accidental movement of the toothed wheel 70, and the play indicating means 12.

From the foregoing it will be apparent that one player, by manipulation of the chute 30, 15 may direct the flight of the missile from the chute 16, and that the other player will release the impact member 40, in an attempt to intercept the flight of the missile and change its direction of flight. If the second mentioned player be unsuccessful in intercepting the flight of the missile, the same will enter the strike compartment and register a strike against the player. If, however, the second mentioned player failed to release the impact member, the missile may then enter either the ball or strike compartment, as heretofore described. If, on the other hand, the second mentioned player is successful in intercepting the flight of the missile and causes its projection in the reverse direction to the contracted 20 portion 40, of the chute 16, the same will drop upon the member 51, rock the lever 52, about its pivotal point 53, release the bar-like member 61, to the action of its spring 65, and effect a spinning movement of the gear 70, of the play indicator 12. When the play indicator 12, comes to rest the stationary pointer 11, will indicate the 25 result of the play, and the scoring will be done accordingly.

From the foregoing it is apparent that the 30 present invention provides a new and novel game apparatus so constructed and arranged that it may be adapted to various games of the type in which the flight of a missile is determined by an impact member, which apparatus is simple in 35 construction, easy of operation, and which combines the two elements, skill and chance.

Having thus described the invention, what is claimed as new and what it is desired to secure by Letters Patent of the United States, is:

1. A game apparatus comprising in combination, a two part chute, one part being stationary and one part movable and through which a missile may be rolled in directed flight and discharged into the stationary chute section, an impact member movable across said stationary chute section, a missile adapted to be rolled through said chute sections and to be intercepted in its flight by said impact member, means for trapping said missile, and a play indicator operated by said missile when the same is intercepted in its flight by said impact member.

2. In a game apparatus, a base, an adjustable standard projecting from said base, a stationary chute section carried by said base, a movable chute section pivotally mounted upon the upper end of said adjustable standard and discharging into said stationary chute section, a series of traps at one end of the stationary chute member, said traps being adapted to receive a missile as it travels through the stationary chute section, and means for intercepting the passage of a missile through the stationary chute section.

3. In a game apparatus, a base, an adjustable standard projecting from said base, a stationary

chute section carried by said base, a movable chute section pivotally mounted upon the upper end of said adjustable standard and discharging into said stationary chute section, a series of traps 5 at one end of the stationary chute member, said traps being adapted to receive a missile as it travels through the stationary chute section, and means for intercepting the passage of a missile through the stationary chute section, said last 10 mentioned means comprising a spring actuated impact member movable across the stationary chute member.

4. In a game apparatus, a base, an adjustable standard projecting from said base, a stationary chute section carried by said base, said stationary chute section being inclined and provided at its lower end with a plurality of traps, a movable chute section pivotally mounted on said vertically adjustable standard, said movable chute section being inclined and having its lower end overlying the upper end of the stationary chute section whereby a missile in its travel through 20 the movable chute section will be discharged into

the stationary chute section, and means for intercepting a missile in its passage through the stationary chute member.

5. In a game apparatus, a base, an adjustable standard projecting from said base, a stationary chute section carried by said base, said stationary chute section being inclined and provided at its lower end with a plurality of traps, a movable chute section pivotally mounted on said vertically adjustable standard, said movable chute section being inclined and having its lower end overlying the upper end of the stationary chute section whereby a missile in its travel through the movable chute section will be discharged into the stationary chute section, and means for intercepting a missile in its passage through the stationary chute member, 5 said last mentioned means comprising a spring actuated impact member, and means for pivotally mounting said impact member upon one of the side walls of the stationary chute section and the base. 10 15 20

JOHN GRAUER.
